UNITED STATES PATENT OFFICE

WALTER P. RANKIN, OF BOSTON, MASSACHUSETTS

PROCESS OF TREATING LEATHERBOARD

Application filed July 22, 1930. Serial No. 469,707.

My invention relates to a method of treating leatherboard particularly for use in the manufacture of shoe heels.

Experience has demonstrated that laminated articles constructed from ordinary leatherboard, the cut face of which is drab and toneless, present to prospective purchasers edge faces having a flat, unattractive appearance with the result that definite sales resistance to laminated leatherboard articles is created notwithstanding the well known advantages of leatherboard over leather.

The principal object of my invention is to devise a method of treating leatherboard whereby the product of the method may be used in constructing laminated articles having improved edge faces that render the article, for example a shoe heel, attractive to purchasers.

To the accomplishment of this object, and such others as may appear hereinafter, the features of the invention reside in a process of treating leatherboard hereinafter described and particularly pointed out in the appended claim, which possesses advantages readily apparent to those skilled in the art.

My invention will best be understood from an inspection of the accompanying drawings illustrating leatherboard, treated in accordance with the preferred mode of practicing the invention, and a shoe heel constructed from the treated leatherboard, in which:

Figure 1 is a view, in perspective, of the treated leatherboard;

Fig. 2 is a view, in elevation, of a shoe heel in the manufacture of which the treated leatherboard is used; and

Fig. 3 is a view, in perspective, of a heel lift as an example of one of the many shapes that may be dinked from the treated leatherboard, or treated individually as may be desired, and then used in building a heel.

In the drawings the thickness of depth of the coating at the treated face of the leatherboard relative to the thickness of its untreated or virginal edge face has been somewhat exaggerated in order to present a clear optical distinction between the two.

Referring to the drawings I take a sheet of leatherboard manufactured in the usual

way from any desirable formula and provide at least one face thereof with a thin coat 5 of some substance characteristically differing from leatherboard. By "coat" I mean a layer or covering of any substance, applied to the face coated, preferably one having a color in contrast to the natural drab color of the leatherboard. The coat, at the time of its application to the leatherboard, may be a solid or a liquid. Preferably the coat 5 is a liquid coating material which may be uniformly applied to the leatherboard. The liquid coating material may be paint or lacquer and may form a surface coat or act as a stain or dye and penetrate the leatherboard below the coated surface.

I propose to cut the large sheet into smaller pieces and such pieces cut from the treated leatherboard may be heel lifts 6 (Fig. 3) for manufacturing a shoe heel 7 (Fig. 2). The heel lifts 6 may be dinked out of the treated leatherboard in any usual manner. When the heel lifts 6 are stratified, superposed or built up in the usual manner, care being taken to separate the coated surfaces, they form the heel 7.

As shown in Fig. 2 the coats 5 on the lifts 6 appear on the edge face of the heel 7 as narrow spaced streaks 8 of a contrasting color which relieve the drab effect of the leatherboard and impart an attractive variegated appearance to the circumferential surface of the heel. When the heel is filled and burnished after the usual heel finishing practice, either off or on the shoe, the more or less definite lines of demarkation are toned down, one edge shade or color being merged into another so that the streaks are not so sharply defined.

It will be apparent to those skilled in the art that the heel lifts 6, or any other shape of piece for any particular laminated article that is to be formed, may be provided with the coat 5 individually after they have been dinked out of an untreated sheet of leatherboard. For a more pronounced streaky effect both flat faces may be coated.

Having thus described my novel method and one mode of practicing it when employing its underlying principle, yet recognizing

that some modifications and changes may be made without departing from its spirit and scope, what is claimed as new is:—

That improvement in the art of treating leatherboard which consists in staining at least one flat face thereof with a liquid capable of penetrating said face and of a color for tinting the edge face of the leatherboard throughout the depth of said penetration, dinking out heel lifts from the treated leatherboard, and building the heel lifts into a heel.

In testimony whereof I affix my signature.
WALTER P. RANKIN.
